VACUUM CLEANER

Clarence Everett Stevens, Greenwich, Conn., assignor to Electrolux Corporation, Dover, Del., a corporation of Delaware

Application March 13, 1941, Serial No. 383,082

6 Claims. (Cl. 220—56)

My invention relates to vacuum cleaners and more particularly to vacuum cleaners of the enclosed bag type.

This type of cleaner includes a hollow casing within which is disposed a dust bag and a motor-fan unit. The casing is formed with an opening through which the bag may be inserted and removed and a removable closure member is provided for closing this opening and usually also serves to clamp the open mouth of the dust bag in place.

My invention contemplates an improved means for securing the closure member in place over the opening, this means also serving as a handle for lifting and carrying the vacuum cleaner. In accordance with my invention, a bail is pivoted to the casing and is arranged to be pivoted into contact with the outer surface of the closure member so as to clamp it in place. A central portion of the bail, which extends beyond the closure member, is formed as a handle. Inasmuch as the bail serves both to retain the closure member in place and as a handle, it is necessary to provide positive locking means for holding it in contact with the closure member, as otherwise the force applied to the handle portion of the bail for lifting the cleaner would disengage the bail from the closure member. In accordance with my invention, I preferably provide one or more spring-pressed latch members for locking the bail. While a single latch member may be sufficient for this purpose, two might be preferable so as to avoid the possibility of the bail becoming released in the event that one latch member is accidentally disengaged. The likelihood of both latch members being accidentally released at the same time is not great.

My invention has the advantages of providing for easy and quick removal and replacing of the closure member, while at the same time providing a convenient handle for carrying the vacuum cleaner.

Further objects and advantages of my invention will be apparent from the following description considered in connection with the accompanying drawings, which form a part of this specification, and of which:

Fig. 1 is a side view of a vacuum cleaner including one embodiment of my invention;

Fig. 2 is a top view of a portion of the vacuum cleaner shown in Fig. 1;

Fig. 3 is a cross-sectional view taken on the line 3—3 of Fig. 2;

Fig. 4 is a cross-sectional view taken on the line 4—4 of Fig. 2;

Fig. 5 is a cross-sectional view taken on the line 5—5 of Fig. 2;

Fig. 6 is a cross-sectional view taken on the line 6—6 of Fig. 1;

Fig. 7 is a side view of a portion of a vacuum cleaner including another embodiment of my invention;

Fig. 8 is a top view of the portion of the cleaner shown in Fig. 7;

Fig. 9 is a cross-sectional view taken on the line 9—9 of Fig. 8; and

Fig. 10 is a side view of a complete vacuum cleaner shown in a vertical position.

Referring more particularly to Figs. 1 through 6, reference character 10 designates a hollow casing which is provided with runners or the like 11 for supporting it horizontally upon a horizontal surface. Suitably mounted within the casing 10 in well known manner is a motor-fan unit and a dust bag. The construction of the dust bag is the same in both embodiments and the parts thereof which are pertinent to my invention are shown in detail in Fig. 9. As here illustrated, the dust bag 12 is formed with an open mouth which is secured to an annular flange 13 of a dust bag ring 14. The ring also includes a radial flange 15 which carries a gasket 16 of rubber or other suitable material. The left-hand end of the casing 10, as viewed in either Fig. 1 or Fig. 9, is open and has secured thereto a ring 17 which forms a seat against which the gasket 16 of the dust bag ring is adapted to be clamped by a closure member for the opening. This closure member is designated generally by reference character 18 in the embodiment illustrated in Figs. 1 through 6 and by reference character 18' in the second embodiment. In either case the closure member includes an inlet opening 19 to which may be connected a hose or the like 20, the opposite end of which is connected to a suction nozzle 20a.

In the first embodiment the closure member 18 is shown as a casting. At diametrically opposite points the casting is formed with a substantially flat surface 21, the upper edge of which is rounded or beveled, as is shown at 22 in Fig. 4. Pivotedly secured to opposite sides of the casing 10 is a generally U-shaped bail 23. As shown more particularly in Fig. 6 a pin 24 extends through aligned apertures formed in the bail, in the casing 10 and in a reinforcing member 25. The outer end of the pin is provided with a head while a lock ring 26 engages an annular groove formed near the inner end of the pin to thereby pivotally secure the bail 23 to the casing. The

bail includes a pair of substantially parallel portions 27 which, when the bail is in the cover closing position shown in Fig. 1, appear as extensions of channel member 28 secured to either side of the casing. The portions 27 are joined together at one end by means of a handle portion 29.

Adjacent to the juncture of the handle portion and the straight portion 27, the bail 23 is formed with substantially flat surfaces 30, the lower edges of which are rounded or beveled, as is shown at 31 in Fig. 4. The surfaces 30 are so positioned on the bail as to engage the flat surfaces 21 on the closure member when the bail is pivoted in a counterclockwise direction to the position shown in Fig. 1, and to clamp the closure member tightly against the gasket 16 of the dust bag ring. Immediately above the surfaces 30, the bail is formed with projecting lugs 32 which strike surfaces 33 formed on the closure member to thus limit pivotal movement of the bail in a counterclockwise direction.

The closure member 18 is formed with recesses 34 which are located in surfaces 35 disposed radially inwardly from and to the left of the surfaces 21, as viewed in Fig. 2, these recesses being shown more particularly in Fig. 3. The bail 23 is formed with slots 36 extending therethrough within which are pivotally mounted latch members 37. As shown more particularly in Fig. 5, a pin 38 extends across the slot 36 near the bottom thereof and passes through an aperture formed in the lower end of latch 37. The latch is formed with a projecting portion 39 which is adapted to be received within the recesses 34 formed in the cover member. This projecting portion is provided with an inclined surface 40. A spring 41 having a forked end 42 pivoted on the pin 38 is disposed between the latch member 37 and a surface 43 formed on the bail and acts to pivot 40 the latch member in a clockwise direction, as viewed in Fig. 3, so as to engage the projecting portion 39 within the recess 34. The upper end of the latch member extends through the slot 36 so that it may be pressed by the operator's finger to the left, as viewed in Fig. 3, so as to retract the projecting portion 39 from the recess 34.

The operation of the above-described device is as follows:

With the parts in the position shown in the figures, the surfaces 30 on the bail press against the surfaces 21 on the cover member so as to force the cover member against the gasket 16 on the dust bag ring, to clamp the gasket against the ring 17 of the casing. The engagement of the projecting portions 39 on the latch members 37 within the recesses 34, where they are retained by the springs 41, locks the bail in this position. Consequently, the handle portion 29 may be grasped and the vacuum cleaner picked up thereby without any danger of releasing the bail from engagement with the closure member. Even should the operator accidentally contact one of the latch members 37 so as to release it, the bail would still be retained in place by the other latch member, and it is very unlikely that both latch members would be accidentally contacted at the same time.

When it is desired to remove the closure member, the latch members 37 are simultaneously pivoted in a counterclockwise direction, as viewed in Fig. 3, so as to retract the projecting portions 39 from the recesses 34, while at the same time the handle portion 29 is pulled upwardly. This causes the bail to be pivoted in a clockwise direc-

tion, as viewed in Fig. 1, about the pins 24 so as to disengage the surfaces 30 on the bail from the surfaces 21 on the closure member. Thereafter, the closure member may be removed and the dust bag taken out for the purpose of emptying it.

In order to replace the parts, the dust bag is inserted through the open end of the casing and the closure member put in place. The bail is then pivoted in a counterclockwise direction, as viewed in Fig. 1. The beveled surfaces 31 on the bail will first strike the similar surfaces 22 on the closure member and will force the closure member tightly against the gasket 16. Further pivoting of the bail brings the flat surfaces 30 into contact with the flat surfaces 21. At the same time, the inclined surfaces 40 on the projecting portions 39 of the latch members 37 contact the upper edges of the surfaces 35 on the cover, and the latch members are thus pivoted in a counterclockwise direction, as viewed in Fig. 3. The parts are so arranged and dimensioned that when movement of the bail is arrested by contact of the lugs 32 with the surfaces 33 on the closure member, the projecting portions 39 of the latch members are in alignment with the recesses 34 in the closure member, and are forced into these recesses by the springs 41.

In the embodiment illustrated in Figs. 7 through 10, the bail is again designated generally by reference character 23 and includes side portions 27, which are pivoted at one end to the casing 10 by means of pins 24, and which are connected together at their other ends by means of the handle portion 29.

The cover member 18' includes an inner plate 50 to which is secured an outer shell 51. The plate and shell are formed with aligned apertures for accommodating the inlet port 49. Secured to the outer surface of shell 51 is a strip of metal 52 which extends upwardly from the center of the cover member to the periphery thereof. The upper end of the strip 52 is formed as a knob or hook 53 which is adapted to be received within a recess 54 formed in a channel member 55 carried by the top of the cleaner. This hook serves to retain the closure member 18' in position, even when it is not locked in place by the bail.

The strip 52 is formed with an opening 56 therethrough and behind this opening the shell 51 is shaped to form a recess having a shallow portion 57 and a deep portion 58. A latch member 59 is disposed within the shallow portion and a spring 60 is retained in the deep portion and tends to force the lower enlarged end of the latch 59 outwardly through the opening 56.

Secured to the handle portion 29, as by bolts 61, is a leaf spring 62 which is bowed away from the handle portion and towards the closure member, the dimensions of the parts being such that the center of the leaf spring bears against the center of the closure member with sufficient force to hold the latter in place.

With the parts in the positions illustrated in the figures, the leaf spring 62 is locked in position by means of the latch member 59, the lower edge of which engages the upper edge of the spring. Consequently, the handle 29 may be grasped to lift the cleaner without there being danger of releasing the bail from contact with the closure member. However, when it is desired to remove the closure member, the latch member 59 is pressed inwardly by the finger, against the force of spring 60, until it is flush with the strip 52, whereupon the bail may be pivoted upwardly so as to remove the leaf spring from con-

tact with the closure member. The closure member is still retained in place by means of the hook 53 engaging the recess 54, but it may be grasped and removed from the casing 10.

In order to replace the parts, the hook 53 is engaged with the recess 54 so as to hold the closure member in position, and the bail is pivoted downwardly. The outer surface of the strip 52 is substantially arcuate and has a radius of curvature less than the radial distance between the axis of the pivot pins 24 and the central point of spring 62. Consequently, as the bail is pivoted downwardly towards closing position, the spring strikes the strip near the upper part of the latter and slides therealong, which causes the spring 62 to be distorted and hence to exert force against the closure member. Due to the curvature of the outer surface of the latch member, the leaf spring is able to pass thereover by forcing the latch member inwardly. As soon as the spring has cleared the latch member, the latter snaps back under the influence of the spring 60 to lock the leaf spring, and hence the bail, in position.

While I have shown two more or less specific embodiments of my invention, it is to be understood that this has been done for purposes of illustration only, and the scope of my invention is not to be limited thereto, but is to be determined by the appended claims.

What I claim is:

1. In a vacuum cleaner, a hollow casing formed with an opening, a removable closure member for said opening, a bail pivotally secured to said casing and having a portion disposed so as to engage said closure member to retain the latter in closing position, said bail having a portion forming a handle for lifting said vacuum cleaner, and a spring-pressed latching member operative independently of force applied to said bail for releasably locking said bail against pivotal movement and in engagement with said closure member with the handle portion in operative position.

2. In a vacuum cleaner, a hollow casing formed with an opening, a removable closure member for said opening, a bail pivotally secured to said casing and having a portion disposed so as to engage said closure member to retain the latter in closing position, said bail having a portion forming a handle for lifting said vacuum cleaner, and a spring-pressed latch member carried by said bail and engageable with a recess formed in said cover member and operative independently of force applied to the bail for releasably locking said bail against pivotal movement and in engagement with said closure member with the handle portion in operative position.

3. In a vacuum cleaner, a hollow casing formed with a substantially circular opening, a removable closure member for said opening, a resilient packing between said casing and said member, a bail pivotally secured to said casing and having surfaces formed thereon and positioned so as to engage diametrically opposed surfaces formed on said closure adjacent to the periphery thereof to thereby compress said packing, said bail having a central portion forming a handle for lifting said vacuum cleaner, and spring-pressed latch members carried by said bail adjacent to either end of said handle portion and operative independently of force applied to the bail to releasably engage with recesses formed in said cover member for locking said bail against pivotal movement and in engagement with said closure member with the handle portion in operative position.
4. In a vacuum cleaner, a hollow casing formed with an opening, a removable closure member for said opening, a bail pivotally secured to said casing and having a resilient portion disposed so as to engage said closure member to retain the latter in closing position, said bail having a portion forming a handle for lifting said vacuum cleaner, and a spring-pressed latch member carried by said closure member and engageable with said bail for releasably locking said bail in engagement with said closure member.
5. In a vacuum cleaner, a hollow casing formed with an opening, a removable closure member for said opening, a bail pivotally secured to said casing, said bail having a portion forming a handle for lifting said vacuum cleaner, said bail including a leaf spring bowed from said handle portion toward said casing for engaging said closure member to retain the latter in closing position, and a spring-pressed latch member carried by said closure member and engageable with said spring for releasably locking the latter in engagement with said closure member.
6. In a vacuum cleaner, a hollow casing formed with an opening, a removable closure member for said opening having an outer arcuate surface, a bail pivotally secured to said casing and having a resilient portion disposed so as to engage said surface, the radial distance of said resilient portion from the pivotal axis being greater than the radius of curvature of said arcuate surface, said bail having a portion providing a handle for lifting said vacuum cleaner, and means for releasably locking said resilient portion in engagement with said surface.
